HANDLE FOR PAPER BOXES

Filed Nov. 11, 1922

FIG. 4 FIG. 3

INVENTOR
R. J. Gruenberg
By
Carlos P. Griffin
ATTORNEY.

UNITED STATES PATENT OFFICE.

RAOUL J. GRUENBERG, OF SAN FRANCISCO, CALIFORNIA.

HANDLE FOR PAPER BOXES.

Application filed November 11, 1922. Serial No. 600,397.

To all whom it may concern:

Be it known that I, RAOUL J. GRUENBERG, a citizen of the United States, residing at San Francisco, in the county of San Francisco, State of California, have invented a new and useful Handle for Paper Boxes, of which the following is a specification, in such full and clear terms as will enable those skilled in the art to construct and use the same.

This invention relates to a handle for paper boxes, and its object is to provide a convenient handle for suit boxes or other kinds of boxes, which handle will be suitably connected to the box to carry the material placed therein, and which handle will not seriously weaken the construction of the box when secured thereto.

Another object of the invention is to provide means whereby the slot in the box through which the handle is inserted will be stiffened to such an extent as to avoid any danger of weakening the box owing to the fact that a long slot must be cut for the insertion of the handle.

Another object of the invention is to provide a handle which can be applied to the box with the minimum labor, the handle being of such a form as to waste as little material as possible and be of as simple a form in cutting as possible.

Other objects of the invention will appear as the description proceeds.

An embodiment of the invention is shown in the accompanying drawings in which the same reference numeral is applied to the same portion throughout, but I am aware that there may be modifications thereof.

Fig. 1 shows a common form of telescope box with one of the handles applied to each side thereof.

Fig. 2 is a transverse sectional view of the box shown in Fig. 1, showing the handles fastened thereto.

Fig. 3 is a side elevation of one of the handles.

Fig. 4 is an edge view of one of the handles.

Fig. 5 is a view of one of the handles, in perspective, showing the box corner in dotted lines, and

Fig. 6 is a perspective view of the slot in the box through which the handle is passed when it is to be secured to the box.

Fig. 7 is a perspective view of a slightly modified form of handle which makes use of

the waste cut off in the manner shown in the other figures.

The numeral 1 indicates one of the box sections and 2 the box section which telescopes into section 1. Adjacent the center of the upper corner of each box section there is a slot 3 which is as long as the projecting gripping portion of the handle 4.

Inside the box the handle is provided with a longer gummed portion 5 to which the gripping portion 4 is connected.

In order to close the slot through which the handle is passed when it is to be secured to the box, the box top has a depending flap 6. This flap is pushed back out of the way, as shown in Figure 6, when the handle is to be pushed into place.

When the upper gripping portion of the handle has been pushed through the box top, the tab 6 is pushed outwardly so that it can be glued in place in the plane of the remaining portion of the box side, as indicated in Figure 1.

Since the handle is made of a relatively stiff piece of material, this stiffens the central portion of the box and, as the part 5 is glued to the inside of the box, at opposite ends of the flap 6 there results a relatively strong handle for supporting the load carried by the box.

This construction dispenses with the necessity of extra tabs on the handle, and when applied to folding boxes enables the handle to be easily glued in place and piled flat with the box bottoms and tops.

In Fig. 7 there is shown a handle which may be used with the same box shown in Fig. 1, but which has the tabs 10 and 11 formed at the ends of the handle. This handle has longitudinal portions 5' and handle portions 4' exactly the same as the handle shown in the other figures.

In operation the part 5' is secured to the side of the box while the tabs 10 and 11 are secured to the inside of the top of the box.

What I claim is as follows, but various modifications may be made in the construction shown in the drawings and above particularly described form, within the purview of my invention.

1. A handle for paper boxes, comprising a longitudinally extending gummed member having a gripping portion connected therewith, and a slotted box through which said gripping portion extends, the handle being

glued to the inside of the box, and the top of the box having a depending tab connected therewith and glued to the handle in the plane of the box side.

- 5 2. A handle for paper boxes, comprising a longitudinally extending member having a gripping portion extending therefrom, a slotted box member through which slot the gripping portion of the handle extends, and a depending cut out tab carried by the box top extending over the longitudinal portion of the handle and glued thereto in the plane of the box side.
- 15 3. A handle for paper boxes, comprising

a longitudinally extending member with a 15 D-shaped gripping portion secured thereto, a box slotted to permit said gripping portion of the handle to pass therethrough and a tab as long as the opening in the handle adapted to bend over the longitudinal member which latter is secured permanently to the inside of the box and to said flap whereby the slot in the box is closed. 20

In testimony whereof I have hereunto set my hand this 19th day of October 25 A. D. 1922.

RAOUL J. GRUENBERG.
